FOOT PROTECTOR

Gregg M. Fullarton, Oak Park, and John M. Blessing, Cicero, Ill., assignors to Western Electric Company, Incorporated, New York, N. Y., a corporation of New York

Application May 16, 1934, Serial No. 725,884

7 Claims. (Cl. 36—72)

This invention relates to foot protectors, and more particularly to a safety toe protector for attachment to shoes.

An object of this invention is to provide a simple and efficient safety toe protector which may be readily attached to or removed from a shoe and which may be used with a minimum of discomfort to the wearer.

In accordance with the above object, the invention contemplates a foot protector comprising an attachable metal toe cap having its lower edge slightly inturned and fitting in the groove between the sole and the shoe upper and having resilient backwardly extending wire members also fitting in the groove between the sole and the shoe upper.

Other objects and advantages of this invention will more fully appear from the following detailed description taken in connection with the accompanying drawing, wherein

Fig. 1 is a perspective view of a foot protector embodying the features of the invention;

Fig. 2 is a side view thereof on a reduced scale, showing its application to a shoe, and

Fig. 3 is a vertical detail section on the line 3—3 of Fig. 2.

Referring now to the drawing, the numeral 10 indicates a rigid one piece metal safety foot protector or toe cap of hardened drawn steel or other suitable material hollowed out and arched to fit over the forepart or toe portion of a shoe and slightly spaced from the shoe, particularly across its top, as indicated at 11 (Figs. 2 and 3). The cap 10 is completely open across its bottom, the lower edge of the cap being slightly inturned, as indicated at 12 (Fig. 3), and shaped to fit snugly in the groove between the sole and the upper of the shoe with its lower edge engaging and resting upon the top surface of the sole. Secured by welding, or otherwise, to the outer surface of the cap 10 at its inner open end is a reinforcing strap 13 which also adds to the ornamental appearance of the protector since it gives the toe cap the appearance of the ordinary leather toe cap having an ornamental edging at its rear edge.

Preferably the cap 10 is formed of unhardened steel and after it has been formed to the desired shape the steel is hardened by a suitable heat treatment.

Rigidly attached to the cap 10 at opposite sides adjacent the lower edge thereof and behind the strap 13 by welding, or otherwise, is a pair of resilient backwardly extending cap retaining wire members 14 which lie snugly in the groove between the sole and the upper of the shoe for the

greatest part of their length, as shown clearly in Fig. 2. The free ends of the wire members 14 may have outwardly and downwardly extending portions 15 that extend across the upper surface of the sole from the groove to the edge of the sole and then downwardly across the vertical face of the sole to substantially the lower edge thereof, as clearly shown in Fig. 2, to prevent chafing of the shoe upper by the ends of the wire members. The cap retaining wire members 14 press inwardly with sufficient tension to securely retain the cap 10 in its mounted position on the shoe, but due to their inherent flexibility in all directions about their longitudinal axes they do not interfere with the bending of the foot in stooping or walking, thus adding to the comfort of the wearer. When the shoe is bent during either stooping or walking the rear free ends of the wire members 14 adjacent the portions 15 retain their position in the grooves between the sole and the shoe upper, the wire members between their points of attachment to the cap 10 and the portion 15 merely flexing.

The safety foot protector described above may be made in a variety of shapes to conform to different shoe styles and various sizes and widths in each style and may be provided with a finish to simulate the color of the particular shoe to which it is to be applied.

In use the herein described safety foot protector effectively protects the wearer's toes or forepart of his feet from injury by crushing in the handling of heavy articles in case an article falls or drops upon his feet in any manner, the safety cap being sufficiently rigid to sustain a great crushing force and thereby preventing injury to the feet of the wearer. Furthermore, the safety cap may be used without hindrance to the wearer's movements and with a minimum of discomfort.

Although there is herein shown and described a specific embodiment of this invention, it should be understood that modifications may be made without departing from the spirit and scope of the appended claims.

What is claimed is:

1. A detachable foot protector comprising a rigid arched member shaped to fit over the forepart of a shoe and having its lower edge shaped to rest upon the top surface of the shoe sole, and universally resilient retaining members attached at opposite sides of and extending backwardly of said arched member and shaped to fit between the sole and the upper of the shoe, said retaining members having sufficient stiffness to restrain the protector against slipping forwardly.

2. A detachable foot protector comprising a toe cap of hardened drawn steel having its lower edge shaped to freely rest upon the top surface of the shoe sole, and resilient retaining members 5 circular in cross section attached to said cap at opposite sides extending backwardly and shaped to fit in the groove between the sole and the upper of the shoe, said retaining members having sufficient stiffness to restrain the protector 10 against slipping forwardly.
3. A detachable foot protector comprising a rigid toe cap having its lower edge inturned and shaped to fit in the groove between the sole and the upper of the shoe and freely rest upon the 15 top surface of the sole, and spring wire members attached at opposite sides of and extending backwardly of said cap and shaped to fit between the sole and the upper of the shoe, said wire members having sufficient stiffness to restrain the 20 protector against slipping forwardly.
4. A detachable foot protector comprising a toe cap of hardened drawn steel having its lower edge inturned and shaped to fit in the groove between the sole and the upper of the shoe and 25 to freely rest upon the top surface of the sole and having a reinforcing band along its rear edge, and resilient wire retaining members attached to said cap at opposite sides extending backwardly and shaped to fit in the groove between 30 the sole and the upper of the shoe, said retaining members having sufficient stiffness to restrain the protector against slipping forwardly.
5. A foot protector comprising a readily de-
tachable rigid toe cap having its lower edge surface freely resting upon the top surface of a shoe sole, and resilient retaining members attached at opposite sides of and extending backwardly and inwardly of said cap and fitting in 5 the groove between the sole and the upper of the shoe, said members terminating at and engaging opposite points of the sole under tension.
6. A foot protector comprising a readily de-
tachable rigid metal toe cap having its bottom 10 portion inturned to fit in the groove between the sole and the upper of a shoe, the lower edge surface of the cap freely resting upon the top surface of the sole, and resilient retaining members attached at opposite sides of and extending 15 backwardly and inwardly of said cap and fitting in the groove between the sole and the upper of the shoe, said members terminating at and engaging opposite points of the sole under tension.
7. A foot protector comprising a readily de-
tachable rigid metal toe cap having its lower 20 edge surface freely resting upon the top surface of a shoe sole, and resilient retaining members attached at opposite sides of and extending backwardly and inwardly of said cap and fitting in the groove between the sole and the upper of the shoe, said members at their rear ends formed with 25 outwardly extending portions terminating in vertical portions engaging the vertical edge of the 30 sole under tension.
